UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

INTERRUPTER MECHANISM.

Application filed December 14, 1921. Serial No. 522,432.

My invention relates to an interrupter mechanism that is particularly suitable for use in an ignition system wherein the ignition current is supplied by a battery.

5 One of the principal objects of the invention is to provide an interrupter mechanism wherein the engagement and disengagement of the contacts is effected with great rapidity, the contacts being permitted 10 to remain in engagement for but extremely short periods of time.

A further object of the invention is to provide an interrupter mechanism that is particularly adapted to be operated by a 15 cam formed by providing a flat spot on a shaft forming part of the engine with which the ignition apparatus is associated.

Other objects of the invention will appear as the following detailed description 20 progresses.

In the accompanying drawings illustrating my invention,

Figure 1 is a side elevational view of the 25 interrupter mechanism of my invention, and

Figure 2 is a bottom plan view thereof.

The battery ignition coil and spark plug are diagrammatically illustrated in Figure 1.

Referring to the drawings, reference number 30 10 indicates a shaft forming part of an engine with which the apparatus of my present invention is associated, said shaft 10 being provided with a flat spot 11. At 12 is indicated a plate which is provided 35 with a circular opening 13 for the reception of shaft 10, and with a pair of slots 14-14 for the reception of bolts (not shown) wherewith the plate is secured to the engine in proper angular relation to shaft 40 10. It will be noted that slots 14-14 are elongated in arcs concentric with shaft 10 to permit ready adjustment of the plate 12 to advance or retard the occurrence of the spark.

45 Indicated as a whole by reference character 15 is a lever which is pivotally mounted on plate 12 by pin 16. Lever 15 comprises arms *a*, *b*, and *c*, arms *a* and *b* being located on one side of pivot 16 and arm *c* on the other side of said pivot. Arm *b* carries the follower 17, which at all times is urged into engagement with the shaft 10 by a leaf spring 18, associated with arm *c*. One end of spring 18 is riveted to arm *c*. The 50 other end of said spring bears against and is securely attached to a block 18^a, said block

being conveniently attached to plate 12 by screws, as shown.

The stationary and movable contacts are indicated at 19 and 20, respectively. Stationary contact 19 is carried by a screw 21, which in turn is adjustably mounted in a block 22, said block 22 being supported by plate 12, but being electrically insulated therefrom by suitable di-electric material 60 indicated at 23. The movable contact 20 is carried by the free end of a curved leaf spring 24, the other end of said spring being fixed to a block 25, which is secured to the plate 12 in any suitable manner. The horizontal portion of spring 24 may be stiffened 65 somewhat by an auxiliary leaf spring 26.

The arm *a* of lever 15 carries a finger 27, which has the function of engaging, flexing and tripping spring 24 in the manner presently to be explained. Finger 27 is pivoted to arm *a* at 28, one end of the finger being held in engagement with the arm *a* by a light leaf spring 29. The other end of the finger normally overlies the free 70 end of contact carrying spring 24, and is provided with an inclined end surface 30.

The stationary contact 19 is connected with the insulated side of the ignition circuit, which, in the present instance, includes 80 a battery 31, ignition coil 32, and spark plug 33. Movable contact 20 is grounded to the engine through spring 24, the block 25 and plate 12.

It will be understood that spring 24 normally assumes the position wherein the contacts are separated. Now let us assume that the shaft 10 turns so that the flat spot 11 thereon lies opposite follower 17. Spring 18, by virtue of its inherent strength, and 90 the mechanical advantage afforded by lever 15, moves the follower into engagement with the flat spot 11, and causes finger 27 to depress, and then slip off of the free end of spring 24. As soon as spring 24 is released by finger 27, it recoils past its normal 100 position and causes the movable contact 20 to engage and then quickly disengage the stationary contact 19. A spark is thus caused to pass at the plug 33. As soon as the follower rides off of the flat spot 11, the lever 15 and finger 27 are moved against the pressure of spring 18 to the position shown in Figure 1. In this case, however, the light spring 29 yields to permit the inclined surface 30 of finger 27 to slip past the free end of spring 24 without causing 105 110

engagement of the contacts. The sequence of events just described is repeated once for every revolution of shaft 10.

Having thus described a preferred embodiment of my invention, I do not limit myself to the precise construction or arrangement of parts herein shown or described, but desire to avail myself of all other embodiments of my invention defined by the appended claims.

What I claim as new and desire to secure by Letters Patent of the United States is:

1. An ignition circuit interrupter comprising in combination stationary and movable contacts, spring means normally holding the movable contact out of engagement with the stationary contact, spring actuated means adapted to draw the movable contact away from the stationary contact and then to release the movable contact, the spring means associated with the movable contact being adapted thereupon quickly to recoil under its own tension and cause the engagement and disengagement of the contacts, and engine driven means for controlling the spring actuated means aforesaid.

2. An ignition circuit interrupter comprising a stationary contact, a spring carrying a movable contact, said spring occupying a normal position with said movable contact out of engagement with said stationary contact, and spring actuated means for flexing said spring backwardly away from said stationary contact to build up a recoil pressure in said spring upon movement, in one direction, said spring actuated means releasing said spring to permit it to recoil past said normal position and thereby bring said movable contact into momentary engagement with said stationary contact and said means adapted to move in a reverse direction without bringing the contacts into engagement.

3. An ignition circuit interrupter comprising a stationary contact, a leaf spring carrying a movable contact, said leaf spring occupying a normal position with said movable contact out of engagement with said stationary contact, spring operated actuating means for drawing said spring backwardly from its normal position to establish a recoil tension therein, said spring operated actuating means thereupon releasing said spring and permitting it to snap forwardly past its normal position to bring said movable contact into momentary engagement with said stationary contact, said spring operated actuating means adapted to return to its initial position without causing the contacts to be brought into engagement and engine-operated means for operating said actuating means.

4. An ignition circuit interrupter comprising a relatively stationary contact, a leaf spring carrying a movable contact, said spring normally occupying an unflexed posi-

tion with said movable contact out of engagement with said stationary contact, spring operated actuating means for drawing said spring backwardly from its normal position to establish a recoil tension therein, 70 said spring operated actuating means thereupon releasing said spring and permitting it to snap forwardly, the inertia of said spring and movable contact carrying the latter past said normal position and into momentary engagement with said stationary contact, said spring operated actuating means adapted to return to its initial position without bringing the contacts into engagement, and engine-operated means for 80 operating said actuating means.

5. An ignition circuit interrupter comprising a stationary contact, a movable contact, a spring for impelling said movable contact into engagement with said stationary contact, said spring normally occupying a position with said movable contact out of engagement with said stationary contact, an oscillatory member adapted in one direction of oscillation to flex said spring backwardly away from said stationary contact to establish a recoil tension therein, said oscillating member thereupon releasing said spring and permitting it to snap forwardly 90 past its normal position for bringing said movable contact into engagement with said stationary contact, and tripping means associated with said oscillating member adapted to permit oscillation of said member in the other direction without bringing said contacts into engagement.

6. An ignition circuit interrupter comprising normally separated stationary and movable contacts, a leaf spring fixed at one end and carrying the movable contact at its other end, the free end of said spring adapted, when flexed away from the stationary contact and released, to recoil and in rapid sequence effect the engagement and disengagement of the contacts, spring actuated means adapted to flex and release the free end of said leaf spring, and engine driven means for controlling said spring actuated means, said spring actuated means comprising a lever arm provided with a spring pressed finger adapted when moved in one direction to engage, flex and release the free end of said leaf spring, said finger adapted to slip past the free end of said leaf spring when said finger is moved in the other direction.

7. An ignition circuit interrupter comprising in combination, a controlling shaft having a flat spot, a lever provided with a follower, a relatively strong spring normally holding said follower in engagement with said shaft, a stationary contact, a movable contact normally separated from the stationary contact, a curved leaf spring secured at one end and carrying the movable contact 130

upon its other end, said lever comprising an arm located adjacent the free end of said leaf spring, and a spring pressed finger carried upon said last mentioned lever arm, 5 said finger adapted to engage, flex and release the free end of said leaf spring when the follower rides upon the flat spot of the shaft, and to slip past the free end of the leaf spring when the follower rides off the flat spot onto the cylindrical surface of the 10 shaft.

In witness whereof, I hereunto subscribe my name this 7 day of December, 1921.

WM. W. HAWKINS.
